UNITED STATES PATENT OFFICE.

RAY J. BERTHOUD OF SWANTON, OHIO.

ANTI-RAIL-CREEPER.

1,120,675.

Specification of Letters Patent. Patented Dec. 15, 1914.

Application filed September 19, 1913. Serial No. 790,652

To all whom it may concern:

Be it known that I, RAY J. BERTHOUD, a citizen of the United States, residing at Swanton, in the county of Fulton and State

5 of Ohio, have invented certain new and useful Improvements in Anti-Rail-Creepers; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 A familiar difficulty encountered in railway operation,—especially in double track roads in which the traffic upon the respective tracks is in but one direction,—is the tendency of the rails to overcome their fastenings to the ties and to "creep" longitudinally. Various devices have been proposed for overcoming this difficulty, and some of the "anti-creepers" have, in a measure, proved successful. Usually in these devices 20 a slight longitudinal movement of the rail causes the anti-rail creeper to closely grip the foot of the rail and to prevent its further movement, but the rail must first move in order to cause an effective grip upon its 25 flange. Now, when the reaction from the blows of the passing car-wheels takes place, or when an opposite stress occurs from trains moving in the other direction, the hold of the gripping device is loosened and before 30 it can again properly grip the rail the rail must move slightly beyond the gripping point at which it was held in the first instance. Thus the gripping device is constantly loosening its hold and is often taking 35 a new hold at a point slightly in advance of its last preceding hold, so that while the creep of the rail is retarded it is not wholly prevented. To overcome the 40 difficulty above indicated, some devices of this class are provided with means for positively anchoring the rail-gripping member to an adjacent cross-tie, thus adding to the 45 number of parts, weight and expense of the device.

50 My invention is designed to provide means for overcoming the difficulties above indicated, and, more particularly, to prove a device of the character indicated which shall, independently of the movement of the 55 rail or of any anchorage to the cross-tie, so firmly grip the base or flange of the rail

that the longitudinal movement of the rail will be prevented except by a corresponding movement of the cross-tie with which the clamping device is in contact.

60 A further object of my invention is to provide an anti-creeping device for rails which shall be light, simple, inexpensive and strong and which may be readily applied and removed.

65 To these ends my invention consists of the construction and arrangement of parts hereinafter described, and shown and illustrated in the accompanying drawings, in which—

70 Figure 1, is a top-plan view of my device applied to a rail; Fig. 2, a like view of a modified form of the same; Fig. 3, a perspective view of the device shown in Fig. 1, detached, and Fig. 4, a like view of the device shown in Fig. 2.

75 Like numerals of reference indicate like parts throughout the drawings.

80 In the drawings, 1 is a cross-tie and 2 a track-rail of the usual construction having an ordinary base or flange 3.

85 4 is a plate disposed transversely of and resting against the under side of the base 3. One end of the plate has an upturned hook 5 which engages one margin of the base or flange 3. The opposite end of the plate 4 is provided with an upwardly projecting hook 6 which engages the opposite margin of the rail-base. The plate 4 has, projecting horizontally from about its middle, an elongated arm 7 disposed at an angle to the center line 90 of the rail and having at its outer extremity an upturned hook or flange 8 adapted for engagement with one of the margins of the rail-base. The plate 4 has at its edge opposite the arm 7 a downwardly turned flange 95 or head 9 which when the device is in place rests firmly against that side of the cross-tie toward which the rail tends to "creep", as indicated by the arrows.

100 In the example of my device illustrated in Figs. 1 and 3, the hook 8 is, by means of a powerful lever sprung outwardly and upwardly into engagement with the margin of the rail-base. This slight movement of the arm or lever 7 forces the hooks 5 and 6 inwardly and into a biting engagement with the opposite margins of the rail-base. Now, with the three hooks or lugs 5—6—8 powerfully gripping the edges of the base-plate, the plate 4 with its head 9 is secured rigidly 105 and immovably against the under side of the rail, and the rail is thus prevented from 110

slipping or creeping by reason of the contact of the head 9 with the side of the cross-tie.

In that modification of my device illustrated in Figs. 2 and 4, the hook or lug 8 instead of being sprung over the edge of the rail-base, is, by means of a wedge 10, inserted between the hook 8 and the edge of the rail-base, caused to swing outwardly, with the same effect upon the hooks 5 and 6 as above described. The wedge 10 has a downwardly turned flange or head 11 by means of which the wedge may be powerfully driven into place. The three gripping points are now at the hooks 5 and 6 and the straight inner edge of the wedge 10.

It will be understood that the device here described may be readily attached and may be as readily removed by the use of a tool as indicated, or by driving out the wedge 11. It will also be understood that these anti-creepers are applied to both rails of the track at suitable distances apart, and that they may, if desired, be reversed or doubled in such fashion as to prevent the movement of the rail in either direction.

Having described my invention, what I claim and desire to secure by Letters Patent, is—

1. A rail anchor comprising a plate having at one end a hook adapted for engagement with one margin of the flange of a

track-rail, having at its other end a hook adapted for engagement with the opposite margin of said flange, having also an extended resilient arm normally disposed at an angle to such plate, said extended arm having at its outer extremity a hook adapted to be sprung into operative engagement with one of the flanges of said rail.

2. In a device of the described character, a cross-tie, a track-rail upon the tie, a plate beneath the rail-flange, said plate having at one end a hook engaged with one margin of the rail-flange, having also at its other end a hook engaged with the opposite margin of the rail-flange, having also a head which contacts with the side of said cross-tie, having also a resilient arm disposed at an angle to said plate, said arm having at its outer extremity a hook adapted to spring into operative engagement with one of the margins of the rail-flange, whereby said two hooks first mentioned are held under transverse tension in gripping engagement with opposite margins of the rail-flange.

In testimony whereof I affix my signature in presence of two witnesses.

RAY J. BERTHOUD.
